UNITED STATES PATENT OFFICE.

LUDWIG PRONBERGER, OF BERLIN, GERMANY, ASSIGNOR TO ALFRED PEATS COMPANY, OF NEW YORK, N. Y., A CORPORATION OF NEW YORK.

DESIGN FOR A WALL-COVERING.

No. 38,522.

Specification for Design.

Patented April 9, 1907.

Application filed October 24, 1906. Serial No. 340,416. Term of patent 7 years.

To all whom it may concern:

Be it known that I, LUDWIG PRONBERGER, a subject of the German Emperor, and a resident of Berlin, Germany, have invented a new, original, and ornamental Design for a Wall-Covering, reference being had to the accompanying drawing, in which the figure is a face view of an embossed wall - covering, showing my design.

I claim—
The ornamental design for a wall-covering as shown.

LUDWIG PRONBERGER.
